(57) **CLAIM**

We claim the ornamental design for an aerosol generator, as shown and described.

DESCRIPTION

FIG. 1 is a top front right perspective view of an aerosol generator showing the claimed design;

FIG. 2 is a bottom rear left perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the drawings illustrate portions of the aerosol generator that form no part of the claimed design. The dot-dash broken lines in the drawings illustrate boundaries of the aerosol generator that form no part of the claimed design.

1 Claim, 8 Drawing Sheets
